UNITED STATES PATENT OFFICE.

FRANK MESKER, OF ST. LOUIS, MISSOURI.

BUILDING-FRONT COLUMN.

SPECIFICATION forming part of Letters Patent No. 449,553, dated March 31, 1891.

Application filed May 29, 1890. Renewed February 24, 1891. Serial No. 382,651. (No model.)

To all whom it may concern:

Be it known that I, FRANK MESKER, of St. Louis, Missouri, have made a new and useful Improvement in Building-Front Columns, of 5 which the following is a full, clear, and exact description.

The improved column under consideration is a composite structure, usually of wood, and consisting of three upright members suitably 10 united, and altogether forming a column having the appearance of a pair of pilasters spaced apart by an intermediate member, substantially as is hereinafter described and claimed, aided by the annexed drawings, making part of this specification, in which—

Figure 1 is a view in perspective of the improved column; Fig. 2, a horizontal section of the same, and Fig. 3 a front elevation of the same. The last two named views are upon 15 an enlarged scale.

The same letters of reference denote the same parts.

A A represent the uprights which constitute the pilaster element of the structure, and 20 B represents what may be termed a "sub-column," which is arranged between the uprights A A so as to come opposite the rearward extensions a^1 a^2 of the uprights A A, respectively—that is, the uprights A A are similar, each consisting of a front portion a' and a 25 rear portion a , said rear portion being nar-

rower in width than is said front portion a' . By this means an offset a^2 is formed in each upright A at each side thereof, and the sub-column B is held in the opposing offsets of 35 the uprights A A, substantially as is shown, and the three parts A A B are united by means of cross-strips C, applied to the said parts at the back thereof and secured thereto by means of screws D D, substantially as shown. 40

This composite column can be ornamented as desired, so as to present in front any desirable architectural effect.

When the column is inserted in the building-front, the offsets a^1 a^2 , at the outer sides, 45 respectively, of the column, are utilized in making the connection between the column and the adjacent portions of the building-front.

I claim—

The herein-described composite column, the same consisting of a pair of pilasters A A and the intermediate sub-column B, united by the cross-strips C, substantially as described.

Witness my hand this 30th day of April, 1890.

FRANK MESKER.
